UNITED STATES PATENT OFFICE.

NELSON B. BAILEY, OF SAN FRANCISCO, CALIFORNIA.

HANGER.

Application filed February 16, 1927. Serial No. 168,517.

My invention relates to supporting devices and particularly to a hanger for holding a musical instrument or similar object so that both hands of the user may be free.

6 An object of my invention is the provision of a hanger that is immediately adjustable to any desired length.

Another object of my invention is the provision of a friction element to prevent 10 slipping after the hanger has been adjusted as to length.

15 My invention possesses other objects and features of advantage some of which with the foregoing will be set forth in the following description of the preferred form of my invention which is illustrated in the drawings accompanying and forming part of the specification. It is to be understood that I do not limit myself to the showing made by 20 said drawings and description, as I may adopt variations of the preferred form within the scope of my invention as set forth in the claims.

Referring to the drawings:

25 Figure 1 is a side elevation of my hanger. Figure 2 is a vertical sectional view of the link and friction ring.

30 Figure 3 is a vertical sectional view of the link and friction ring looking in the direction of the arrow 3 in Figure 2.

Broadly my invention comprises a pair 35 of supporting eyelets thru which a double suspension cord is threaded. Both strands of the cord to prevent any movement of the the strands entering the link from opposite sides so that they cross each other. The link cooperates with a friction ring disposed on the link about the crossed portions of the cord to prevent any movement of the 40 cord thru the link after it has been adjusted at a given length. The ends of the cord are then attached in any suitable manner to a coupler which engages the object to be supported.

45 In detail my invention comprises a pair of eyelets 6 and 7 preferably disposed in the ends of a suitable support such as the collar strap 8. Extending thru the eyelets is a double suspension cord 9, preferably a fabric 50 cord, and of sufficient length to permit a wide range of adjustment in the finished hanger. Slidably mounted on the loop of the cord between the two eyelets is an adjusting link 11, thru which both strands of the 55 cord again pass, after being threaded thru the eyelets, one strand entering the link from

each side so that they cross each other within the link. In other words, the suspension cord is first threaded in one direction thru the adjusting link, thru one eyelet, back thru the link, then thru the other eyelet, and back again to the link passing thru it in the opposite direction. In this manner there are two crossed strands and one single strand within the link.

65

Before the ends of the link are closed into abutting position, the link is passed thru the aligned slots 12 provided in the sides of the band-like friction ring 13. In this manner the friction ring is mounted on 70 and surrounds one end of the link so that the crossed strands of the cord must also pass thru it. The link and ring are preferably elliptical as this shape aids in maintaining a proper relation of the parts. The 75 link and friction ring with the cord under tension, form a frictional grip because of the actual engagement of the cord portions and also because of the abrupt change of direction of the cord portions enforced by 80 the link and ring. This grip resists movement of the cord through the parts so strongly with the cord under tension, that the cord will break before slipping. With 85 tension removed from the cord, the ring and link are readily moved to adjust the length of the hanger. After the cord has been crossed upon itself thru the link and friction ring the ends are secured to a suitable coupler 14, such as a hook, which is adapted to 90 engage the object to be supported.

The hanger of my invention will be found particularly adapted for use by musicians playing wind instruments such as the saxophone where both hands of the user are required for playing. My hanger provides a support readily adjustable to the desired 95 length and one that will maintain its adjusted position until changed by the user.

When it is desired to shorten the hanger 100 light pressure is exerted downwardly on the link 11 until the proper length is reached. If the hanger is to be lengthened light pressure exerted upwardly on the friction ring 105 will release the grip on the cords so that the friction ring and link may slide upwardly thus lengthening the hanger to the desired point.

I claim:

1. An adjustable hanger comprising a 110 pair of supporting eyelets; an adjusting link; and a double suspension cord threaded

thru the link, an eyelet, the link again, the other eyelet and the link again.

2. An adjustable hanger comprising a pair of supporting eyelets, a double suspension cord threaded thru said eyelets, and an adjusting link thru which each strand of the double cord extends across the other to the opposite side and thru which the portion of cord between the eyelets is looped.

3. An adjustable hanger comprising a pair of supporting eyelets, a double suspension cord threaded thru said eyelets, an adjusting link thru which each strand of the double cord extends across the other to the opposite side and thru which the portion of cord between the eyelets is looped, and a friction ring disposed on the link about the crossed portions of the cord.

4. An adjustable hanger comprising a collar strap, an eyelet in each extremity of the

strap, a coupler for connecting the device to the thing to be suspended, a double suspension cord connected at its ends to the coupler and extending thru said eyelets, an adjusting link thru which each strand of the double cord extends across the other to the opposite side and thru which the portion of cord between the eyelets is looped, and a friction ring disposed on the link about the crossed portions of the cord.

5. An adjustable hanger comprising a double suspension cord having a loop and an adjusting link thru which each strand of the double cord extends across the other to the opposite side and thru which the loop portion of the cord passes.

In testimony whereof, I have hereunto set my hand.

NELSON B. BAILEY.
